CLAIM

The ornamental design for an airway device, as shown and described.

DESCRIPTION

FIG. 1 is a top view of an airway device, showing our new design;

FIG. 2 is a left side view thereof;

FIG. 3 is a bottom side view thereof;

FIG. 4 is a right side view thereof;

FIG. 5 is a rear view thereof;

FIG. 6 is a front view thereof;

FIG. 7 is a top perspective view thereof; and,

FIG. 8 is a bottom perspective view thereof.

The broken lines and all within illustrate portions of the airway device that form no part of the claimed design.
